United States Patent Office.

SAMUEL WEHRLY, OF SAN FRANCISCO, CALIFORNIA, ASSIGNOR TO HIMSELF AND E. V. SUTTER, OF SAME PLACE.

Letters Patent No. 78,703, dated June 9, 1868; antedated May 4, 1868.

IMPROVED SPURS.

The Schedule referred to in these Letters Patent and making part of the same.

TO ALL WHOM IT MAY CONCERN:

Be it known that I, SAMUEL WEHRLY, of San Francisco, county of San Francisco, State of California, have invented an Improved Spur; and I do hereby declare the following description and accompanying drawings are sufficient to enable any person skilled in the art or science to which it most nearly appertains to make and use my said invention and improvements without further invention or experiment.

The object of my invention is to provide an improved spur for horsemen, and it consists principally in an improved mechanism for attaching the spur quickly and firmly to the boot, thus dispensing with the strap or screws which are used.

To more fully describe my invention, reference is had to the accompanying drawings, forming a part of this specification, of which—

Figure 1 is a side elevation of the spur.

Figure 2 is a side elevation, showing the slide.

Figure 3 is a top view.

Figure 4 is a front view.

Similar letters of reference in each of the figures indicate like parts.

A is a curved metal band, which encircles the heel of the boot, and which has the spur-wheel B supported by the arm C at the back of A, as in ordinary spurs.

To the sides of the band A, and near the front extremities, are attached the retaining-bolts or screws *a a*, beneath which the sliding plate *b* works. To the front end of this plate is attached, by a small projection, the spring *c*, which extends back over the plate *b*. An arm, *d*, extends upwards from this spring, which engages the fixed rack *m*, attached to the side of the band A. The strap *n* is fastened to the sliding plate *b*, and passes beneath the boot in front of the heel.

A curved steel dog, *o*, is fastened to the inner part of the curved band A behind, which enters between the top of the heel and the counter of the boot. The strap *n* is then brought closely against the front part of the boot-heel, thus holding the spur firmly in place. The spring *c* forces the arm *d* against the rack *m*, and holds it wherever desired.

When the spur is to be removed, the spring *c* is raised by means of the projections *r r*, and the slide allowed to slip forward, thus moving the strap *n*, and releasing the dog *o*.

By this device, a neat and substantial spur is obtained, which is free from the difficulties of attaching and taking off, and, at the same time, is so secure as to be almost impossible to lose, this making it very valuable for cavalry.

Having thus described my invention, what I claim, and desire to secure by Letters Patent, is—

A spur, having the dog *o*, the rack *m*, and arm *d*, together with the spring *c* and slotted plate *b*, the whole constructed and operating substantially as and for the purpose described.

In witness whereof, I have hereunto set my hand and seal.

SAMUEL WEHRLY. [L. S.]
